UNITED STATES PATENT OFFICE.

JOSHUA F. AMES, OF ROCKLAND, MASSACHUSETTS.

DESIGN FOR A LASTING-TACK.

SPECIFICATION forming part of Design No. 31,841, dated November 14, 1899.

Application filed August 26, 1899. Serial No. 728,632. Term of patent 14 years.

To all whom it may concern:

Be it known that I, JOSHUA F. AMES, a citizen of the United States, residing at Rockland, in the county of Plymouth and State of Massachusetts, have invented and produced a new and original Design for a Lasting-Tack, of which the following is a specification.

The drawing represents in perspective a lasting-tack, illustrating my design.

The leading feature of my design for a lasting-tack consists of an elongated body portion having substantially equal separated enlargements at its ends and a smooth sharp-pointed continuously-conical extension beyond one of the enlargements in alinement with the body portion. The elongated body portion *a* of the lasting-tack illustrated in the

drawing has substantially equal separated enlargements *b* at its ends and a smooth sharp-pointed continuously-conical extension *d* beyond one of the enlargements, as *c*, in alinement with the body portion *a*. 20

Having fully described my design, what I claim, and desire to secure by Letters Patent, is— 25

The design for a lasting-tack, substantially as herein shown and described.

In testimony whereof I have signed my name to this specification in the presence of two subscribing witnesses.

JOSHUA F. AMES.

Witnesses:

JOHN C. EDWARDS,
EMMA J. BENNETT.
